UNITED STATES PATENT OFFICE

HENRY T. SCHWANDA, OF WINFIELD JUNCTION, NEW YORK

BELT-ADJUSTING SLIDE

Application filed December 12, 1928. Serial No. 325,484.

This invention relates to belt adjusting slides or friction buckles, the object of the invention being to provide a simple, practical and inexpensive form of slide which will efficiently secure the belt in its adjusted position and prevent slipping thereof, while at the same time providing a slide which may be manufactured inexpensively and have a symmetrical and pleasing appearance.

10. A further object of the invention is the provision of an improved slide which, by reason of its construction, can be readily made from flat pearl stock, such as mother-of-pearl, and yet have sufficient strength effectively to hold 15 the belt or other article and prevent slipping thereof.

In the drawings accompanying and forming a part of this specification—

Figure 1 is a front view of this improved 20 slide attached to a belt;

Fig. 2 is a rear view thereof;

Fig. 3 is a cross-sectional view taken on line 3—3, Fig. 1;

Fig. 4 is a view of the slide detached from 25 the belt;

Fig. 5 is a view of a modified form thereof; and

Fig. 6 illustrates the slide shown in Fig. 5 with a belt attached thereto.

Similar characters of reference indicate 30 corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which 40 I employ is for the purpose of description and not of limitation.

The present improved slide comprises any suitable shape of plate 2 of any suitable material, but the construction particularly enables the use of flat pearl stock, such as mother-of-pearl. Preferably to one side of the center line of the plate a pair of crescent-shaped or semi-circular slots 3 are formed, thus providing between the slots a crescent-shaped bar 4 having continuous, unbroken,

curved, substantially parallel edges 5 and 6. At the opposite side of the center line of the plate a straight slot 7 is provided, forming a straight bar 8 around which the end of the belt or other article is located,— 55 the end of the belt, for instance, being sewed,—whereby the slide is attached to the belt. In use the free end of the belt is slipped through the inner crescent-shaped slot and then around the crescent-shaped bar and out 60 through the outer slot of the pair of crescent-shaped slots, in the manner shown in Fig. 1, whereupon the curved edges of the bar impinge so firmly against the curved form of the belt that slippage thereof is prevented, 65 even under considerable pull or strain. When it is desired to release the belt, it is merely necessary to loosen the ends passing through the slots of the slide plate. The curved formation of the bar not only gives 70 sufficient strength thereto to prevent breakage thereof, even when made of mother-of-pearl stock,—since, as is well known to engineers, an arch is a materially stronger structure than one made of angles,—but this curved form of the bar provides a much 75 superior gripping surface on the material to prevent slipping by reason of the fact that the material is required to conform to the shape of the bar thus preventing any pull 80 thereon causing slippage thereof.

In the form shown in Fig. 5 the plate is provided at each side of the center line thereof with a pair of crescent-shaped slots 8 and 9 forming a crescent-shaped bar 10 therebetween, whereby each end of the belt is secured in the manner shown in Fig. 6, without the necessity of sewing either end of the belt. 85

By reason of the arc formation of the slots and bar the slide will accommodate different widths of belts up to certain limits, merely causing the fabric of the belt, if too wide for the slot, to uniformly gather and materially assist in preventing the slipping of the belt. 90

Because of the arc formation of the slots and bar it will be apparent that the slots and bar can be made longer without increasing the width of the plate than would be possible if the same length of slot were made straight. For instance, the slot shown in Fig. 4, if made 95 100

straight, would necessitate a wider slide plate. Thus a comparatively small plate, with the curved form of slot, will accommodate a wider fabric or belt than the same size of plate with straight slots, since the end of the belt attached to the straight bar can be, as it were, gathered in the manner shown in Fig. 1.

I am aware that various forms of slide plates have been patented, but none of them has the symmetrical, uniform and pleasing appearance of the present improvement and is totally unadapted for use with mother-of-pearl stock, and none of them is provided with crescent-shaped slots forming a crescent-shaped bar.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A belt slide comprising a plate having a pair of crescent-shaped slots forming a crescent-shaped bar therebetween and also having a slot-formed bar, said plate having a solid, unslotted portion extending from the inner crescent shaped slot to the slot forming said last bar and greater mid-way of the lengths of said bars than the solid portion between the crescent-shaped slots, whereby said last bar is spaced a greater distance midway of its length from the crescent-shaped bar than the distance between said crescent-shaped slots.

2. A belt slide comprising a plate having a pair of crescent-shaped slots forming a crescent-shaped bar therebetween and also having a slot-formed, straight bar, said plate having a solid, unslotted portion extending from the inner crescent shaped slot to the slot forming said straight bar and greater mid-way of the lengths of said bars than the solid portion between the crescent-shaped slots, whereby said last bar is spaced a greater distance midway of its length from the crescent-shaped bar than the distance between said crescent-shaped slots.

3. A belt slide comprising a plate having a pair of crescent-shaped slots forming a crescent-shaped bar therebetween and all substantially located to one side of the center line of the plate and also having a straight slot forming a straight bar located at the opposite side of the center line of the plate, all of the plate between the inner crescent shaped slot and the straight slot having an unslotted solid form.

4. A belt slide comprising a plate having a pair of crescent-shaped slots forming a crescent-shaped bar therebetween and also

having a slot-formed, straight bar located at the outer edge of the plate, said plate having a solid, unslotted portion extending from the inner crescent shaped slot to the slot forming said straight bar and greater mid-way of the lengths of said bars than the solid portion between the crescent-shaped slots, whereby said last bar is spaced a greater distance midway of its length from the crescent-shaped bar than the distance between said crescent-shaped slots.

5. A belt slide comprising a plate having a plurality of slots forming bars, a pair at least of such slots having a continuously curved or crescent-shaped form forming an unbroken semi-circular bar therebetween all substantially located to one side of the center line of the plate and also having a slot-formed bar at the opposite side of the center line of the plate, said slot-formed bar being located at the outer edge of the plate and comprising a straight bar.

6. A belt slide comprising a plate having a plurality of slots forming bars, a pair at least of such slots having a continuously curved or crescent-shaped form forming an unbroken semi-circular bar therebetween, all substantially located to one side of the center line of the plate, and also having a slot-formed bar at the opposite side of the center line of the plate, said plate having a solid, unslotted portion extending from the inner crescent shaped slot to the slot forming said last bar and greater mid-way of the lengths of said bars than the solid portion between the crescent-shaped slots, whereby said last bar is spaced a greater distance midway of its length from the crescent-shaped bar than the distance between said crescent-shaped slots.

7. A pearl formed plate having therein a plurality of crescent-shaped slots forming a crescent-shaped bar therebetween, said bar having a smooth unbroken curved edge at the top and bottom thereof and also having a slot formed straight bar materially spaced from said crescent-shaped bar all of the plate between the inner crescent shaped slot and the slot of the straight bar having an unslotted solid form.

8. A belt slide comprising a plate having two pairs of crescent shaped slots, each pair forming a crescent shaped bar therebetween, said plate having a solid unslotted portion between the inner crescent shaped slots of the two pairs, greater mid-way of the lengths of said slots than the width of the bars formed between the crescent shaped slots, whereby the two pairs of slots are spaced a greater distance mid-way of their lengths than the distance between the crescent shaped slots of each pair.

Signed at New York, N. Y., this 30th day of November, 1928.

HENRY T. SCHWANDA. 130
